SHIPPING PACKAGE

Frank M. Kelly, Cincinnati, Ohio

Application October 17, 1938, Serial No. 235,321

5 Claims. (Cl. 105—369)

The present invention relates to a shipping package.

An object of the invention is to provide a means of packing or loading a freight car or like conveyance with large and heavy rolls of paper, such as are used in newspaper presses and the like, whereby such rolls are protected against damage during shipment and in the removal thereof from the car or conveyance.

10 Another object of the invention is to simplify and facilitate both the loading and unloading of heavy paper rolls of the character mentioned, with a substantial saving of time, effort, and expense.

15 Another object of the invention is to provide simple and inexpensive, yet effective means, for the accomplishment of the objects stated above.

These and other objects are attained by the means described herein and disclosed in the accompanying drawing, in which:

Fig. 1 is a plan view of a freight car or other conveyance, with roof removed, showing a preferred form of the invention.

Fig. 2 is an elevational view of a paper roll, 25 partly in cross-section, showing a detail of the invention.

Fig. 3 is a view similar to Fig. 1, part being broken away, showing a modification of the invention.

20 Fig. 4 is a view similar to Fig. 3, showing a second modification.

Fig. 5 is a view similar to Fig. 3, showing a third modification.

Fig. 6 is an elevational view of a binder pin or stake, forming a detail of the invention.

The present invention relates to the packaging and shipping of large and heavy rolls of paper such as are used in newspaper printing presses and the like. The losses resulting from damage

40 in shipping and unloading the rolls from freight cars or other large conveyances, have always presented a problem of great concern, and one which has been very difficult of solution. The damage referred to results from several causes,

45 the major one of which is the shifting of the load incident to sudden jarring of the freight car, such as occurs when switching the cars or strongly applying the brakes of a train of cars.

It has been found that shifting of the load not only crushes the rolls and renders them unfit for high speed press work, but it frequently also jams the rolls at the car door, with the result that considerable damage to the rolls occurs in the attempt to unload the car. The rolls when 50 jammed at the car door, are often punctured or

torn, resulting not only in great paper losses, but in losses of time and labor required for breaking the jam and unloading the first few rolls.

The magnitude of the job may be appreciated when it is considered that each roll of paper 5 weighs approximately four-fifths of a ton, and stands between five and six feet high when placed on end. The diameter of each roll approximates three feet. A freight car carries thirty-seven or thirty-eight rolls, and since each roll weighs 10 nearly a ton, it must be evident that the crushing forces resulting from shifting of the load are enormous. These facts also should give some idea of the difficulty that is encountered when the rolls so shift as to foul the car doorway in 15 such manner that no one roll may normally be extracted to break the jam there occurring. The elimination of the disadvantages and difficulties above mentioned, is one of the primary objects 20 of the present invention.

With reference to the accompanying drawing, 7 indicates a freight car or other large conveyance having a floor 8, sides 9 and 10, and opposite ends 12 and 13. Intermediate the ends thereof, the car or conveyance generally is provided with 25 the access openings or doorways such as 14 and 15, through which the car or conveyance may be loaded and unloaded. In most instances, the doorways are about midway between the ends 12 and 13 of the car or conveyance. 30

The characters 17 indicate the rolls of paper above described. Usually, but not always, the car or conveyance is of a proper width for receiving three rolls transversely of the floor 8, as shown in Figs. 1, 3 and 4. In some instances, 35 however, it is necessary to stagger the rolls as shown in Fig. 5. When the rolls fit into the car or conveyance as illustrated by Fig. 1, the method of composing the entire package, or of loading the car or conveyance, will be practiced 40 in accordance with the present invention as follows:

At the opposite ends of the car, six rolls are tightly packed in contacting relationship, thereby forming what may be termed a "tight-pack", or 45 a tight-packed unit of six rolls. The remaining rolls located between the tight-pack units and the doorway limits of the car are "loose-packed", that is, they are not placed in intimate contact in the rows which extend lengthwise of the car. 50 In this way, it is generally possible to load the car floor, exclusive of the doorway region, with thirty-three rolls of paper. After having tight-packed and loose-packed the rolls as explained, five additional rolls are placed upon the floor in the region 55

of the doorway, and these are tightly bound together so as to provide a buffer unit which will weigh between four and five tons. The buffer unit obviously will serve to maintain the loose-packed rolls in position, because of the difficulty with which the buffer unit may be moved by the jarring action of the car or conveyance. By preference, the buffer unit is so composed as to have three rolls 17a, 17b and 17c arranged with their axes in a plane which is oblique to the side walls of the car. This arrangement has been found very satisfactory as a means of keeping at least one of the rolls of the buffer unit, in position for easy extraction through the car doorway, after cutting the binder 18.

As disclosed in Fig. 1, the rolls of the buffer unit are bound together to form a heavy solid mass, by driving pins or stakes, such as 19 down into the hollow core 20 of the outside rolls of the buffer unit, and then applying the binder 18 so as to bind the heads 21 of the pins or stakes in the manner illustrated by Fig. 1. In the event that the binder 18 be in the form of a wire, rope, cable or the like, it may be found desirable to groove the head of the stake or pins as indicated at 22, to prevent the binder from slipping off the upwardly extending head or projection of the stake 19. At this point in the description, it may be noted that the cores of most of the rolls are not indicated, this being due to the fact that the rolls are generally wrapped or enveloped in a suitable wrapper having closed ends. In general, however, each roll will have a central hollow core such as 20.

35 In the modified form of the invention as disclosed in Fig. 3, the buffer unit is formed by merely fastening a strap or other binder 23 about the outer peripheries of the exterior rolls which form the unit. Such binder may be a strap of metal or any other suitable material, and one or more of them may be applied at different elevations upon the unit. So far as the ease of easy unloading of the car is concerned, the modified form of the invention disclosed in Fig. 3 performs in substantially the manner explained in connection with Fig. 1.

In the second modification, Fig. 4, the rolls are tight-packed and loose-packed as previously explained, but instead of forming the buffer unit with the use of five tightly bound paper rolls, there are seven rolls employed in the buffer unit. The binding means, in this modification, may be like those of Figs. 1, 2 and 3. As in the disclosures of Figs. 1 and 3, the loose-packed rolls which are near the doorway can never shift to a position in front of the rolls of the buffer unit and thereby foul the doorway. In other words, the buffer unit precludes any such movement of loose-packed rolls at the edges of the doorway, as would result in disposition of the loose-packed rolls between the buffer unit and the door of the car.

Fig. 5 discloses the method of loading resorted to when the car or conveyance is too narrow to permit the formation of straight rows of paper rolls transversely of the car floor. It should be understood that the car of Fig. 5 may be equipped with a multiple roll buffer of any of the forms previously described herein.

70 The structural details, such as the character of the pins or stakes, and the binder, obviously may be changed and modified, within the scope

of the appended claims, without departing from the spirit of the invention.

I claim:

1. A shipping package which comprises a freight conveyance having a floor, opposed sides, and opposite ends, at least one of said sides being provided intermediate the ends with a doorway through which the conveyance may be loaded and unloaded, a group of heavy paper rolls placed on end in tightly packed relationship at each end of the conveyance, other rolls on end packed loosely from the tightly packed groups and toward the doorway, and a middle group of rolls standing on end at the doorway and tightly secured together to form a heavy bodily unrestrained shift-resisting buffer controlling shifting of the adjacent loosely packed rolls at the opposite sides of the buffer group of rolls, the means for securing the buffer group, in unitary formation, comprising a series of pins extending upwardly from the cores of said rolls, and a securing band tightly encircling the series of extending pins.

2. A freight buffer unit comprising a group of five heavy hollow-core paper rolls standing on end with the axes of the cores in substantial parallelism and with one roll centrally disposed relative to the remaining four outer rolls, substantial pins inserted in the upper ends of the four outer roll cores, said pins each including a head extending outwardly from the core of a roll, and a wire tying in the heads to preclude lateral shifting of the rolls.

3. A freight buffer unit for the purposes described, comprising a group of five heavy paper rolls standing on end, one roll being a central roll with the axes of all the rolls in substantial parallelism, substantial pins extending from corresponding ends of the four rolls which substantially surround the central roll, and a binding element tying in the pins to hold said four rolls against the fifth central roll to preclude separation of the rolls at the tied ends thereof.

4. A freight buffer unit for the purposes described, comprising a group of heavy paper rolls standing on end arranged to substantially encircle at least one central roll, all of said rolls having their major axes in substantial parallelism, and means near corresponding ends of the encircling rolls, providing abutments beyond the limits of the roll ends, for tying the corresponding ends of the encircling rolls tightly against the center roll or rolls.

5. A shipping package which comprises a freight conveyance having a floor, opposed sides, and opposite ends, at least one of said sides being provided intermediate the ends with an access aperture for entering the conveyance and loading and unloading same, a plurality of heavy rolls placed on end upon the floor, and packed in the conveyance from the opposite ends thereof toward the access aperture at the side of the conveyance, leaving an area of the floor at the aperture free for the reception of a group of rolls, said group of rolls in the region of the access aperture being tied together at a location above and beyond the upper ends of said group of rolls, to form a heavy solid unitary buffer opposing shifting of those rolls which are located between the buffer group and the opposite ends of the conveyance.

FRANK M. KELLY.
